Primary Examiner — Joseph Kukella*Assistant Examiner* — Lavon M. Amerson(74) *Attorney, Agent, or Firm* — Winston Hsu(57) **CLAIM**

The ornamental design for a baby carriage, as shown and described.

DESCRIPTION

FIG. 1 is a top, front, right side perspective view of a baby carriage showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, front, right side perspective view of the baby carriage of FIG. 1, shown in a condition of use.

The broken lines depict portions of the baby carriage that form no part of the claimed design. The broken lines showing a container in FIG. 8 depict environmental subject matter that forms no part of the claimed design.

1 Claim, 8 Drawing Sheets(56)
